UNITED STATES PATENT OFFICE.

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

TAR-EXTRACTOR APPARATUS AND METHOD.

1,337,984.

Specification of Letters Patent. Patented Apr. 20, 1920.

Application filed December 2, 1918. Serial No. 264,968.

To all whom it may concern:

Be it known that I, JOSEPH BECKER, (assignor to The Koppers Company, a corporation of Pennsylvania,) a citizen of the United States, residing in Pittsburgh, in the county of Allegheny and State of Pennsylvania, have invented a new and useful Improvement in Tar-Extractor Apparatus and Methods, of which the following is a specification.

This invention relates to an improved method of, and apparatus for, the extraction of tarry matter from gases, as for example the gases produced as a by-product in the manufacture of coke. The improved method consists primarily in passing the gas through perforated plates and automatically controlling, by the pressure difference between the outer and inner faces of said plates, the area of exposed perforations that determines the velocity of flow of the gases and the consequent velocity of impingement of the tar particles upon said plates; and the method further consists in effecting such control by utilizing said pressure difference to regulate, in respect of said plates, the level of the accumulated tar in which they are partly immersed, and in keeping the exposed perforations clear by flowing fresh tar upon and through said plates. And the invention further consists in the apparatus for accomplishing this method of control, and in such other features of structure and method as are hereinafter more fully described and claimed.

In the accompanying drawings which form a part of this specification and show an illustrative embodiment of my invention,

Figure 1 is an elevation and partly sectional view of apparatus, shown somewhat diagrammatically, to be used in the practice of the method (the tar extractor being outlined on reduced scale in respect to the control device):

Fig. 2 is a vertical section of the tar extractor, on the line 2—2 of Fig. 3;

Fig. 3 is a section on the line 3—3 of Fig. 2;

Fig. 4 is a section on the line 4—4 of said Fig. 2;

Fig. 5 is an enlarged fragmentary detail of the perforated plates in the tar extractor bells;

Fig. 6 is an enlarged section horizontally through a side of one of the hexagonal bells of the tar extractor; and

Fig. 7 is an enlarged sectional view of one of the diaphragm motor valves.

In said drawings, 20 shows the gas inlet through which the gas to be cleansed enters the lower or receiving chamber 21 of the tar-extractor. This chamber is separated from the main chamber 22 by a partition 23. From the receiving chamber the gas flows upward through the upright, open stand-pipes 24, of which in this particular instance there are seven. Capped over each of these pipes is a bell or inverted basket of hexagonal form, the sides of which are frames 25 provided with pairs of perforated plates 26, 27, the inner plate, 26, of each pair having its perforations 28 smaller and staggered with the large perforations 29 of the outer plate of the pair, as indicated in Figs. 5 and 6. These bells are suspended from the removable beams 30, supported in the brackets 31 fixed to the inner face of the upper part of the body of the apparatus. The open lower ends of these bells extend nearly to the bottom of the main chamber 22, and are immersed in the accumulated tar so that the gas flowing up through the pipes 24 must pass through the perforated plate sides of the bells.

The gas that has passed out from within the bells into the main body of the chamber 22 is discharged from the latter through one or both of the gas outlets 32, 33, according to the subsequent treatment or disposition of such gas.

In passing through the plates 26, 27, with their staggered perforations, the gas, flowing from a higher pressure contained within the bells to a lower pressure maintained outside the bells, has a velocity proportioned in a certain ratio to the pressure differential, and such velocity, imparted to the tar particles carried in the gas, causes these tar particles to impinge and to be deposited upon the said plates, and as this deposition continues, the tar flows down the plates and accumulates in the lower part of the chamber 22, which thus serves as a tar reservoir. The completeness with which the flowing gas is thus free from its tar depends upon maintaining the proper velocity of impinge-

ment of the tar particles upon the plates, and this depends upon properly maintaining the pressure differential between the gas inflowing into the bells and the gas outflowing from the chamber 22. The required velocity depends on the quantity of tar carried in the inflowing gas, and when the differential necessary to maintain such velocity has been determined for gas of a given tar content, such differential needs to be maintained notwithstanding that it is constantly being affected by changes in the volume of the gas passing through the apparatus. And for any given volume of the flowing gas, the differential will be determined by the area of effective perforations which the plates expose to the gas above the level 34 of the tar accumulated in the lower part of the chamber 22. The area of the effective perforations above the tar level 34 will vary not only with changes of that level, relative to the height of the perforated plates, but also with the clogging or clearing of the perforations that are above that level. There is a special tendency to such clogging when the gas contains a large amount of naphthalene and other solid matter in proportion to its tar content. When the gas contains comparatively little tarry matter, so that the accumulating of fresh tar is slow, there is also an increased tendency for the perforations in the immersed portions of the plates to become clogged with the depositing of solid matter from the more or less stagnating, or but slowly outflowing, accumulation of tar in which the lower portions of such plates are immersed.

The maintaining of the proper area of effective perforations exposed to gas flow is accomplished by raising or lowering the tar level 34 in respect of the height of the perforated plates, changing the extent of their immersion in such tar. And this change of tar level, or of extent of immersion of the baffle plates, is effected in positive automatic response to any changes that occur in the above mentioned pressure differential, and automatically compensates such changes. In the illustrated apparatus, the lowering of the predetermined required differential will cause a raising of the tar level, and the raising of the predetermined required differential will cause a lowering of the tar level. There is also provision for maintaining a circulation of fresh tar, both by the inflowing of fresh tar into the tar accumulating in the lower part of the chamber 22, and also by the spraying of fresh tar over and through the exposed perforations of the perforated plates above the tar level 34.

The tar accumulating in the lower portion of chamber 22 flows out through the tar outlet 35, and thence directly through the outlet pipe 36 when the hand valve 37 in said pipe is open. When such valve 37 is closed,

the outflowing tar must pass through the bypass 38, around said valve 37. This bypass may be adjusted or shut off by the hand valves 39, 40. It is normally opened and shut off by the motor-diaphragm valve 41. A tar inlet 42 provides for the introduction of fresh tar into the tar accumulated in the lower portion of chamber 22. This tar inlet communicates directly, through the tar inlet pipe 43, with a pump connected to the outside, tar reservoir. Such tar inlet 42 may be shut off by the hand valve 44, which is normally open, but its direct communication with the tar reservoir is normally shut off or limited by the hand valve 45, and the inflow passes wholly or mainly through the bypass 46 around said valve 45. This bypass may be shut off or adjusted by the hand valves 47, 48, and is normally opened and closed by the motor-diaphragm valve 49. With the several hand valves adjusted to allow flow of tar through the outlet bypass 38 and the inlet bypass 46, such inflow and outflow will be determined by the motor-diaphragm valves 41 and 49 respectively pertaining to said bypasses 38 and 46. When the outflow motor-diaphragm valve 41 is open and the inflow motor-diaphragm valve 49 is closed, the tar level 34 in the chamber 22 will lower; and reversely when the said outflow motor-valve 41 is closed and the inflow motor-valve 49 is open. The opening and closing of these two motor-valves, to cause raising or lowering of the tar level 34, is effected by a controller that automatically responds to any changes of the pressure differential between the inflowing and outflowing gas, the controller being connected, through the pipe 50, with the inflowing gas and, through the pipe 51, with the outflowing gas. Such controller may be of any suitable kind, but there is here shown a form of the standard Tagliabue controller, the air pressure connections and gages being of such standard type, and a special differential float control being provided by the present invention. This controller is connected with an air pressure supply, through the pipe 52, and such air pressure is transmitted to or shut off from the connection pipes 53 and 54 that respectively lead to the outlet motor-valve 41 and the inlet motor-valve 49. When the controller admits air pressure to either the pipe 53 or the pipe 54, the corresponding motor-valve, 41 or 49, is forced shut, closing the corresponding bypass, 38 or 46, and shutting off the corresponding inflow or outflow of tar. When the controller cuts off air pressure from the pipe 53 or pipe 54, the corresponding motor-valve, 41 or 49, opens under the force of its own spring, and opens the corresponding outflow or inflow bypass, 38 or 46, for the corresponding outflow or inflow of tar. The operation of this form

of standard controller may be readily understood from Fig. 1. When the inflowing gas increases in pressure in the tar extractor apparatus, such increased pressure is transmitted through the pipe 50 to the interior of the bell float 55 in the controller, and raises such float; and reversely when the pressure transmitted through connection pipe 50 decreases. Or when the outflowing gas increases in pressure in the tar extractor apparatus, such increased pressure is transmitted through the connection pipe 51 to the controller's float-chamber 56 and depresses the bell float 55; and reversely when the gas pressure transmitted through pipe 51 decreases. The float stands at normal only when the predetermined required differential exists between the inflowing gas pressure, transmitted through pipe 50, and the outflowing gas pressure, transmitted through pipe 51. When the float is standing at normal in the controller, the float-stem 57 is standing with its fixed collars 58 and 59 in such relation to the actuating levers of the air valves 60 and 61 that both of these valves are open, admitting air to both of the connection pipes 53 and 54, thus holding both of the motor-valves 41 and 49 closed, shutting off the by-passes 38 and 46, so that the only flow of tar through the outlet 35 and inlet 42 is what may be allowed by the set adjustment of the hand-valves 37 and 45 in the direct outlet and inlet pipes. If there is then either an increase of inflowing gas pressure, transmitted through the pipe 50, or a decrease of the outflowing gas pressure, transmitted through the pipe 51, the float 55 and its float-stem 57 will rise, and the collar 58 will release the lever of the air valve 60, which will close under its own spring; thereby shutting off the air from the connection pipe 53 and allowing the motor-valve 41 to open, opening the tar-outlet by-pass 38, and thereby lowering the tar level 34, the tar inlet motor-valve remaining closed because the air valve 61 remains open during this action of the air valve 60. As the tar level 34 lowers, more of the plate perforations are exposed to the passing gas, and the differential decreases, whereupon the float and float-stem lower and again open air valve 60, admitting air to the air line 53 and again closing the motor-valve 41 in the tar outlet by-pass. If now the inflowing gas pressure, transmitted through the pressure line 50, decreases, or the outflowing gas pressure, transmitted through the pressure line 51, increases, further lessening the differential, the float 55 and its float-stem 57 will drop still lower and thereby release the lever of the air valve 61 and allow that valve to be closed by its own spring, thus shutting off air to the air line 54 and allowing the motor-valve 49 to open the tar inlet by-pass 46, allowing an inflow

of fresh tar that will raise the tar level 34, thus reducing the area of plate perforations exposed to the flowing gas and increasing the differential. Thereupon the float and float-stem again rise, lifting the lever of the air valve 61 and so admitting air to the air line 54 and motor-valve 49 and so again closing the tar inlet by-pass 46, the air valve 60 remaining open and holding the tar outlet motor-valve 41 closed during these actuations of the air valve 61 controlling the motor-valve 49 of the tar inlet by-pass. All of these valve movements are gradual, to preclude fast or extreme variations in the maintaining of the desired differential pressure in the tar extractor.

The admission of fresh tar through the tar inlet 42 serves to keep up a circulation in and prevent stagnating of the tar accumulated in the lower portion of chamber 22 of the tar extractor. Further provision for introduction of fresh tar, to keep clear the perforations in the baffle plates, is made by connecting the tar inlet pipe 43, below the by-pass 46, with a branch pipe 62 provided with a hand valve 63 and arranged to conduct a flow of tar into the circle-pipe 64, from which there radiate into the lower chamber of the tar extractor the several leader pipes 65, each of which has its inner end connected to a vertical pipe 66 that leads up through the middle of one of the corresponding gas stand-pipes 24 and discharges a flow of tar upon the top of the umbrella shaped cap 67 that is suspended within the top of each of the bells of perforated baffle plates. The fresh tar flowing over the tops of these caps 64 is discharged from their edges against the interior faces of the perforated baffle plates and flows down such plates and through their perforations, tending constantly to keep such perforations clear of stoppage, and also further maintaining the circulation of fresh tar around the immersed lower portions of the perforated baffle plates. Any undue variations of the tar level 34 brought about by this inflow of fresh tar from the circle-pipe and spray caps are compensated by the pressure differential control previously described. The circulation of fresh tar upon and through the perforated plates, serving to keep their exposed perforations clear of stoppage, also furthers the uniformity of operation of the differential pressure control.

The invention may also be applied to the extraction of other liquid or solid matters from gas, and if utilized for the extraction of other solid matters, the liquid employed in varying the pressure differential or in keeping baffle plates clear of stoppage, may be water or other suitable liquid.

My invention as hereinabove set forth is embodied in a specific illustrative form of apparatus and method, but the invention

may of course be embodied in various other forms of apparatus and method within the scope of the claims hereinafter made.

I claim:

- 5 1. In a tar-extractor apparatus, in combination: a chamber for the flowing gas and accumulating tar; perforate baffle-plates in said chamber, for effecting deposition of tar from the flowing gas, said plates being arranged to be partially immersed in the accumulating tar; means, operable by power derived independently of the gas flow for varying the extent of such immersion of said plates, to vary the perforate area they expose to the gas flow; and a controller to operate said means positively in direct automatic response to changes in the pressure differential of the gas flow through said baffle-plates; substantially as specified.
- 10 2. In a tar-extractor apparatus, in combination: a chamber for the flowing gas and accumulating tar; perforate baffle-plates in said chamber, for effecting deposition of tar from the flowing gas, said plates being arranged to be partially immersed in the accumulating tar; means, operable by power derived independently of the gas flow for raising and lowering the tar level in said chamber; and a controller to operate said means in automatic response to changes in the pressure differential of the gas flow through said baffle-plates; substantially as specified.
- 15 3. In a tar-extractor apparatus, in combination: a chamber for the flowing gas and accumulating tar; perforate baffle-plates in said chamber, for effecting deposition of tar from the flowing gas, said plates being arranged to be partially immersed in the accumulating tar; an outlet for said tar; an inlet for introducing fresh tar into said chamber; valves for said outlet and inlet; and a controller to operate said valves in automatic response to changes in the pressure differential of the gas flow through said baffle-plates; substantially as specified.
- 20 4. In a tar-extractor apparatus, in combination: a chamber for the flowing gas and accumulating tar; perforate baffle-plates in said chamber, for effecting deposition of tar from the flowing gas, said plates being arranged to be partially immersed in the accumulating tar; an outlet for said tar; an inlet for introducing fresh tar into said chamber; motor-valves for said outlet and inlet; and a pneumatic controller to operate said motor-valves in automatic response to changes in the pressure differential of the gas flow through said baffle-plates; substantially as specified.
- 25 5. In a tar-extractor apparatus, in combination: a chamber for the flowing gas and accumulating tar; perforate baffle-plates in said chamber, for effecting deposition of tar from the flowing gas, said plates being arranged to be partially immersed in the accumulating tar; and piping and spraying means for introducing fresh tar and flowing it over the exposed perforate area of the baffle-plates; substantially as specified.

ranged to be partially immersed in the accumulating tar; and piping and spraying means for introducing fresh tar and flowing it over the exposed perforate area of the baffle-plates; substantially as specified.

6. In a tar-extractor apparatus, in combination: a chamber for the flowing gas and accumulating tar; perforate baffle-plates in said chamber, for effecting deposition of tar from the flowing gas, said plates being arranged to be partially immersed in the accumulating tar; piping and spraying means for introducing fresh tar and flowing it over the exposed perforate area of the baffle-plates; means for varying the extent of the immersion of said baffle-plates in the accumulating tar; and a controller to operate said immersion varying means in automatic response to changes in the pressure differential of the gas flow through said baffle-plates; substantially as specified.

7. In an apparatus for extracting comminuted matter from gas, in combination: a chamber for the flowing gas; perforate baffle-plates in said chamber, for effecting deposition of the comminuted matter by the impact of its particles upon said baffle-plates as the gas flows through the perforate area of said plates; a reservoir for liquid in the lower part of said chamber, to effect partial immersion of said baffle-plates; means, operable by a power derived independently of the gas flow for varying the extent of such immersion of said plates, to vary the perforate area they expose to the gas flow; and a controller to operate said means positively and in direct automatic response to changes in the pressure differential of the gas flow through said baffle-plates; substantially as specified.

8. In an apparatus for extracting comminuted matter from gas, in combination: a chamber for the flowing gas; perforate baffle-plates in said chamber, for effecting deposition of the comminuted matter by the impact of its particles upon said baffle-plates as the gas flows through the perforate area of said plate; a reservoir for liquid in the lower part of said chamber, to effect partial immersion of said baffle-plates; means, operable by a power derived independently of the gas flow for raising and lowering the liquid level in said chamber, to vary the perforate area exposed by said baffle-plates to the gas flow; and a controller to operate said liquid level varying means in automatic response to changes in the pressure differential of the gas flow through said baffle-plates; substantially as specified.

9. In a method of controlling the operation of tar extractors, the utilizing of changes in the pressure differential of the baffled gas flow to effect automatically and positively, by power derived independently of the gas flow, the compensating changes

of immersion of the baffling in the accumulating tar, to maintain uniformity in the velocity of the gas flow; substantially as specified.

- 5 10. In a method of controlling the operation of tar extractors, the utilizing of changes in the pressure differential of the baffled gas flow to effect automatically, by power derived independently of the gas flow 55
 10 the raising and lowering of the level of the accumulating tar, to maintain uniformity in the velocity of the baffled gas flow confined above such tar level; substantially as specified.
- 15 11. In a tar-extractor apparatus, in combination: a chamber for the flowing gas and accumulating tar; baffle plates in said chamber, for effecting deposition of tar from the flowing gas, said plates being arranged to 60
 20 be partially immersed in the accumulating tar; means, operable by a power constantly in reserve, to vary the extent of such immersion of said plates, to vary the baffle area they expose to the gas flow; and a controller operable for releasing said means 65
 25 positively in direct automatic response to changes in the pressure differential of the gas flow against said baffle-plates; substantially as specified.
- 30 12. In an apparatus for extracting comminuted matter from gas, in combination: a chamber for the flowing gas; baffle-plates in said chamber, for effecting deposition of the comminuted matter by the impact of its 70
 35 particles upon said baffle-plates as the gas flows against the baffle area of said plates; a reservoir for liquid in the lower part of said chamber, to effect partial immersion of said baffle-plates; means operable by a power 75
 40 constantly in reserve, to vary the extent of such immersion of said plates, to vary the baffle area they expose to the gas flow; and a controller for releasing said means positively and in direct automatic response to 80
 45 changes in the pressure differential of the gas flow against said baffle-plates; substantially as specified.
13. In an apparatus for extracting comminuted matter from gas, in combination: 85
 50 a chamber for the flowing gas; baffle-plates

in said chamber, for effecting deposition of the comminuted matter by the impact of its particles upon said baffle-plates as the gas flows against the baffle area of said plates; a reservoir for liquid in the lower part of said 55
 chamber, to effect partial immersion of said baffle-plates; air power means for varying the extent of such immersion of said plates, to vary the baffle area they expose to the 60
 gas flow; and a float controlling said means positively and in direct automatic response to changes in the pressure differential of the gas flow against said baffle-plates; substantially as specified.

14. In an apparatus for maintaining constant differential pressure between the inlet and outlet pressures of gas flow, in combination: a means for directing the gas flow; power means constantly in reserve for varying the cross-sectional area of the gas flow; 70
 and a float controlling said means positively and in direct automatic response to changes in the pressure differential of the gas flow; substantially as specified.

15. In a tar-extractor apparatus, in combination: a surrounding chamber for the flowing gas and accumulating tar; a bell chamber within said chamber, having perforate baffle plates through which gas passes from one chamber into the other to effect deposition of the tar from the flowing gas, said baffle plates being partially immersed in the accumulating tar; gas-flow passages respectively communicating with the interior of the bell and with the chamber surrounding 85
 the bell; and means, controlled in response to changes in the pressure differential of the gas flow through said baffle plates, for raising and lowering the tar level in said chamber, to vary the perforate area the baffle 90 plates expose to the gas flow; substantially as specified.

In testimony whereof I have hereunto set my hand in the presence of two subscribing witnesses.

JOSEPH BECKER.
